J. Ernest Chaught Co

UNITED STATES PATENT OFFICE.

WILLIAM J. DUNN, OF MONTREAL, QUEBEC, CANADA.

INTERNAL-COMBUSTION ENGINE.

1,377,877.

Specification of Letters Patent. Patented May 10, 1921.

Application filed March 5, 1920. Serial No. 363,625.

To all whom it may concern:

Be it known that I, WILLIAM J. DUNN, a subject of the King of Great Britain, and resident of the city of Montreal, in the Province of Quebec and Dominion of Canada, have invented certain new and useful Improvements in Internal-Combustion Engines, of which the following is a full, clear, and exact description.

10 This invention relates to improvements in valves for internal combustion motors, and the object of the invention is to provide a simple and easily constructed valve gear comprising a minimum number of 15 parts.

A further object is to provide for the quick intake and release of gas to enable an engine to operate efficiently at high speed.

20 A still further object is to provide means for efficiently lubricating and cooling the valve gear.

The device consists briefly of a jacketed head containing a pair of tubular valves. Gas conduits are connected to one end of 25 said valves and a driving mechanism to the opposite end, so that the valves may be rotated within the head to bring ports therein into and out of communication with ports in the head. Means are provided for lubricating the valves throughout their length 30 and also for insuring a flow of cooling medium uniformly around the valves.

In the drawings which illustrate the invention:—

25 Figure 1 is a fragmentary vertical cross sectional view of an engine, in the central plane of one of said cylinders.

Fig. 2 is a longitudinal section on the line 2—2, Fig. 1.

40 Fig. 3 is a fragmentary plan view.

Referring more particularly to the drawings, 11 designates the cylinders of an engine provided with a water jacket 12 and preferably cast *en bloc*. 13 designates a cylinder head having a water jacket 14 communicating with the cylinder jacket. Within the head jacket, and suitably supported, is a longitudinally disposed tubular portion 15 having two bores preferably arranged 45 axially parallel. Each of these bores is slightly tapered from end to end, as clearly shown in Fig. 2, and each bore opens through the ends of the head. Within the bores are revolvably mounted tubular valves 16 and 17 having ports 18 and 19 formed 50 through the walls thereof and positioned to

communicate with ports 20 and 21 leading through the head to the cylinders. The length of the ports 20 and 21 is substantially equal to the diameter of the cylinders 60 and the ports are located as nearly as possible on the diameter of the cylinder. In order to reduce as much as possible the volume or capacity of these ports and to reduce the size of openings in the cylinder 65 head without restricting any of the ports these ports may be inclined and allowed to merge where they communicate with the cylinder as clearly shown in Fig. 1.

It will be noted that the walls of the 70 valves are of uniform thickness throughout and also that the walls of the part 15 inclosing the valves are as much as possible of uniform thickness throughout in order to insure uniform expansion and contraction 75 and thus avoid imperfect fitting of the valves.

An oil passage 22 is provided in the part 15 parallel with the valves. Ducts 23 are provided radiating from this passage and communicating with the valve receiving bores at points between the ports, so that the ducts will never bring the interior of the valves into communication with the oil passage. An oil supply pipe 24 communicates with 80 one end of the passage and an overflow pipe 25 with the opposite end. Oil is preferably supplied from the crank case of an engine or any suitable reservoir by means of a pump connected to the pipe 24 and the surplus of oil allowed to return to the crank case or reservoir through the pipe 25. In this way there will always be an adequate supply of oil to lubricate the valves.

85 A manifold 26 is connected to the end of the head containing the large ends of the valves. This manifold contains the inlet and exhaust gas passages, which communicate directly with the valves. This manifold serves to hold the valves in place in the head.

At the opposite end of the head, the valves are closed and project beyond the head. A pair of matched gears 27 connect the valves for revolution. One of the valves is driven 105 by any suitable means such as a gear 28 which may be connected by a chain with the crank shaft.

In order to insure adequate and uniform cooling of the valves, a rib 29 is provided extending from the part 15 to the top of the head jacket, thus dividing the jacket longi-

tudinally into two parts. A cooling medium outlet 30 is provided at one end of the head. The rib 29 preferably extends into this outlet to at least the end of the head, so as to insure a uniform flow of cooling medium up each side of the cylinder block and over each valve.

While the device has been illustrated only as applied to an engine having two cylinders, 10 it will be obvious that it is in no way limited to any particular number of cylinders. For a four-cycle engine, the valves will obviously be driven at half the crank shaft speed and for a two-cycle engine at crank 15 shaft speed. For each type of service, the ports will obviously require to be suitably proportioned to insure proper area of opening and proper duration of opening.

The operation of the device is as follows;—The valves are revolved by power 20 taken from the engine shaft, the incoming gas flows through one valve and at proper intervals through the ports of this valve and the ports 20 into the cylinders, where it 25 is compressed and exploded in the usual manner. The exhaust gases flow at properly timed intervals through the ports 21 and 19 into the valve 17, and from it through the manifold 26. During the entire operation 30 of the engine, oil is circulated under pressure through the passage 22 and a certain proportion of it flows through the ducts 23

to the outer surfaces of the valves and separates over the engaging surfaces of the valves and head portion 15. The cooling 35 medium from the cylinder jacket flows up into each side of the head jacket and, owing to the rib 29 which divides the jacket into two parts, a circulation is compelled around each of the valves. 40

Having thus described my invention, what I claim is;—

1. In an internal combustion engine, a cylinder, a head therefor, a pair of tubular valves revolubly mounted in said head, ports 45 in the valves and head, means at one end of the head for revolving said valves, and a single manifold member attached to the opposite end of the head having inlet and outlet passages therein communicating with 50 the respective valves, said manifold holding the valves in operative position in the head.

2. In an internal combustion engine, a cylinder, a head therefor, a pair of valves located in said head, ports between the 55 valves and cylinder, said ports merging into one another adjacent their entrance into the cylinder, whereby a single port opening is presented to the cylinder having an area substantially the same as the area of either 60 of said ports.

In witness whereof, I have hereunto set my hand.

WILLIAM J. DUNN.
